UNITED STATES PATENT OFFICE.

ABRAHAM L. RICHARD, OF LYNN, MASSACHUSETTS.

WELTED BOOT OR SHOE.

1,288,200.

Specification of Letters Patent.

Patented Dec. 17, 1918.

Application filed December 22, 1917. Serial No. 208,352.

To all whom it may concern:

Be it known that I, ABRAHAM L. RICHARD, a citizen of the United States, and a resident of Lynn, in the county of Essex and State of Massachusetts, have invented an Improvement in Welted Boots or Shoes, of which the following description, in connection with the accompanying drawings, is a specification, like characters on the drawings representing like parts.

This invention relates to a boot or shoe having a welt and has for its object to provide a welted boot or shoe of superior merit as will be described. To this end, the welted boot or shoe is provided with a substantially thin insole free from a feather and having a lip formed by turning over the edge of the insole blank, which leaves the insole within the boot or shoe free to have the upper contact with the body portion of the insole at the junction of the lip with said body portion, whereby a smooth joint is formed between the upper and insole, which is free from projections or sharp edges which cause discomfort to the wearer of the boot or shoe especially after the same has been wet and dried.

The featherless insole is capable of being made materially thinner than insoles provided with a feather, which results in a material saving in the weight and cost of the insole and also results in the production of a more flexible and comfortable shoe, and further enables heretofore waste material, especially thin leather to be utilized as insoles for welted boots and shoes. So also, it effects a material saving in labor, as the operation of channeling insoles now commonly practised with leather insoles is avoided.

These and other features of this invention will be pointed out in the claims at the end of this specification.

Figure 1. represents a welted shoe embodying this invention.

Fig. 2, a plan view of the insole with a portion of the upper and welt sewed thereto.

Fig. 3, a section of the shoe on an enlarged scale to illustrate the featherless feature of the insole, the section being taken on the line 3—3, Fig. 2.

Fig. 4, a detail in section on an enlarged scale showing the outer sole attached to the welt, and

Fig. 5, a section on the line 5—5, Fig. 2, through the heel portion of the insole to show the reinforcement therefor.

Referring to the drawing, 10 represents the insole; 12, the upper; 13, the welt, and 14 the outer sole of a welted boot or shoe.

In accordance with this invention, the insole 10 is formed without a feather, such as now commonly used in insoles of welted shoes. The featherless insole 10 is made by turning or folding over an insole blank at its outer edge at the shank and fore part 65 to form a lip 15, indicated by dotted lines in Fig. 2, and shown in section in Figs. 3 and 4. The folded-over lip 15 as shown clearly in Figs. 3 and 4, provides the insole with preferably a rounded or curved edge portion 16 at the shank and fore part, against which the upper 12 bears when the said upper and welt 13 are sewed to the lip 15 by the inseam stitches 17 in the same manner as now commonly practised. The outer 70 sole 14 is sewed to the welt by the fair stitches 18 in the usual manner.

By providing the boot or shoe with a featherless insole, so that the upper when sewed to the lip 15 of the insole, is brought 80 into contact with the rounded edge 16 of the insole formed by the junction of the lip with the body portion, a materially more comfortable and flexible shoe is obtained, especially for ladies, as the insole is capable 85 of being made of materially thinner stock, which renders the shoe more flexible, and inasmuch as the insole within the shoe is provided with a rounded edge, which is firmly held down to the outer sole by the 90 inseam stitches, no opportunity is presented for the formation of ridges or hard, sharp projections for the foot to press upon, especially after the shoe has been wet and dried in service, and, as a result, a more 95 comfortable wearing shoe is obtained.

Furthermore, the featherless insole, enables the insole to be made of substantially one-half the thickness of an insole provided with a feather, and, as a result, thin leather 100 which is not of sufficient thickness to permit of being channeled, and which now is not available for insoles of welted shoes, is capable of being employed for a featherless insole, at a material saving in the cost 105 of making welted boots and shoes, as by such use, a saving in stock is effected, also in labor, time, etc., as the operation of channeling is dispensed with.

The thin featherless insole is provided at 110 its heel portion 19 with a reinforcement 20, which may be of fiber board, or other sub-

stantially firm material, which reinforcement is cemented or otherwise affixed to the heel portion 19 of the insole, and strengthens the heel of the insole so as to enable the upper to be firmly nailed thereto, as shown in Fig. 5.

The thin insole permits the body portion of the latter to be brought in contact with the outer sole so as to rest thereon (see Fig. 4), and, as a result, the usual filler between the insole and the outer sole now commonly employed may be omitted and the cost of the shoe thereby reduced besides increasing the flexibility.

15 While the insole is relatively thin as compared with channeled insoles, it is nevertheless of sufficient thickness to enable the folded over lip to retain its folded over position against the pressure of the needle guide 20 of sewing machines now employed for securing the upper and welt to the insole of welted shoes by the inseam stitches 17, and the latter are passed through the lip at its base where the lip joins the bottom of the 25 insole, and thus forms a seam between the welt and the upper in close proximity to the last for the so-called table or guide of the fair stitch machine, which if so desired, enables the fair stitches to be brought closer 30 to the last with a consequent saving in the outer sole, as the latter may be made narrower and the welted shoe made to approximate closely the neat and finished appearance of a turn shoe.

35 Claims:

1. A welted boot or shoe having a featherless insole provided at the shank and fore part with a folded over lip capable of retaining its folded over position and resisting the pressure of a needle guide exerted

laterally against it, and having a substantially flat unfolded heel portion attached to said shank portion, and having the upper and welt sewed to the said lip at the base thereof where it joins the bottom of said insole, with the upper within the shoe contacting with the turned over lip at the rounded edge thereof and substantially at the line of stitches which unite the upper and welt to the insole, and having the upper overlapping the substantially flat heel portion and secured thereto within the edge thereof and interposed between said heel portion and the heel of the shoe.

2. A welted boot or shoe having a featherless insole provided at the shank and fore part with a folded over lip capable of retaining its folded over position and resisting the pressure of a needle guide exerted laterally against it, and having a substantially flat heel portion integral therewith, and having the upper and welt sewed to the said lip at the base thereof where it joins the bottom of said insole, with the upper within the shoe contacting with the turned over lip at the rounded edge thereof and substantially at the line of stitches which unite the upper to the insole, the body portion of the insole being relieved from transverse strain and free to move toward the outer sole into a position below a horizontal plane through said stitches, said upper overlapping the substantially flat heel portion and secured thereto within the edge thereof and interposed between the said heel portion and the heel of the shoe.

In testimony whereof, I have signed my name to this specification.

ABRAHAM L. RICHARD.
